UNITED STATES PATENT OFFICE.

ARTHUR S. COWAN, OF BOSTON, MASSACHUSETTS.

DESIGN FOR A TEXTILE FABRIC OR SIMILAR ARTICLE OF MANUFACTURE.

Application filed November 15, 1926. Serial No. 19,731. Term of patent 7 years.

To all whom it may concern:

Be it known that I, ARTHUR S. COWAN, a citizen of the United States, residing at Boston, in the county of Suffolk, State of Massachusetts, have invented a new, original, and ornamental Design for a Textile Fabric or Similar Article of Manufacture, of which the following is a companying drawing, forming part thereof. The figure is a face view of a piece of textile fabric, or similar article of manufacture showing my new design.

I claim:

The ornamental design for a textile fabric or similar article of manufacture, as shown.

ARTHUR S. COWAN.
